RAILWAY TRANSPORT CAR

Arthur I. Anderson, St. Paul, and Keith F. Solimar, Minneapolis, Minn., assignors to Butler Manufacturing Company, Kansas City, Mo., a corporation of Missouri

Filed Aug. 1, 1966, Ser. No. 3,279

Term of patent 14 years

(Cl. D66—1)

FIG. 1 is a side elevational view of a railway transport car embodying our new design, the other side being substantially the same in appearance;

FIG. 2 is a top plan view of same;

FIG. 3 is an end view of same, the other end being substantially the same in appearance; and

FIG. 4 is a sectional view taken generally along line 4—4 of FIG. 1 in the direction of the arrows.

The dominant features reside in the solid portions.

We claim:

The ornamental design for a railway transport car, as shown and described.
